Frederick W. Barker

ATTORNEY.

UNITED STATES PATENT OFFICE.

CHARLES J. PAULSON, OF BROOKLYN, NEW YORK, ASSIGNOR OF ONE-THIRD TO
MATTHEW V. O'MALLEY, OF BROOKLYN, NEW YORK.

COIN-SELECTING MECHANISM.

Application filed February 4, 1925, Serial No. 6,685. Renewed May 19, 1928.

This invention relates to selective mechanism for the delivery of designated coins, entered through a slot, to a predetermined passage or receptacle, and for rejecting spurious coins, such as disks, washers, slugs, light weight disks and the like, to the end that designated or true coins only will be applied to the purpose for which such coins are intended.

10 A coin operated telephone is an example of one of the uses for my invention, which is however not limited to such use.

15 My improvements include the use of a coin guide hung upon an inclined frame capable of being swung and displaced by the action of a coin or other device passing through the coin slot; also a weighted shield that is hung upon lugs extended from the guide, which shield closes against the guide

20 to retain the coins or spurious coins laterally in their passage, but said shield being adapted to become separated from the guide to permit rejection of a spurious coin when another coin is entered through the slot;

25 also an eccentrically pivoted device in the form of a magnet, to engage magnetically the disks, said device having one longer arm that projects from the frame into the path of the coins and spurious coins, said

30 device having a shorter arm which impales a washer whose weight is imposed on the longer arm; also a guide channel to direct true coins along a predetermined path when the weight of such coins is imposed upon the longer arm of the pivoted device to depress it.

Other features and advantages of my invention will hereinafter appear.

In the drawing:

40 Figure 1 is a front elevation of my improved mechanism, including a part of the frame on which it is mounted and a portion of an enclosing coin box including the slot therein.

45 Fig. 2 is a side view thereof, the frame appearing in section, dotted lines showing the swung-back positions of the coin guide and shield under the influence of an entered coin.

50 Fig. 3 is a similar view of the guide and shield in their normal positions.

Fig. 4 is a front view of the coin guide.

Fig. 4^a is a side view thereof.

Fig. 5 is a front view of the shield.

Fig. 5^a is a side view thereof, and

55 Fig. 6 is a detail side view of the eccentrically pivoted device, in the form of a magnet, which serves to reject all kinds of spurious coins and permits the free passage of true or designated coins only.

60 In the representation of my invention herein illustrated let 1 indicate a frame upon which the mechanism is mounted, 2 an element composed of sheet material which I call the coin guide, 3 another element which I call the shield, and 4 that part of a coin box having the coin receiving slot 5. The frame 1 is disposed in an inclined position beneath the slot 5. Said frame has a rounded edge 6 to support the guide 2 by 65 means of lugs 7 that extend rearwardly from said guide and have curved engaging surfaces 8, whereby said guide may be swung, using said frame edge 6 as a fulcrum. The upper end of guide 2 is provided with an inclined nose-piece 9, that extends up nearly to the slot 5 to be in the path of a coin entered therethrough, so that a passing coin will fall upon the incline of said nose-piece 9, and by its weight, 70 or with the addition of pressure will cause the upper part of the guide to swing rearwardly upon its fulcrum, thus also causing the lower part of the guide to swing forwardly. The coin having displaced nose-piece 9 will slide down the guide against the forward surface thereof, said guide, due to the preponderance of its weight below the fulcrum swinging back to its normal 75 position against the frame. The guide is provided with side walls having suitable curvatures which direct the path of the coin. Thus there is a curved wall portion 10 at one side that deflects the coin to the opposite side, where it meets a curved wall portion 11 that deflects it back to a curved wall portion 12, these deflections tending to retard the speed of descent, and the curved wall portion 12 guiding the coin laterally toward an opposite, downwardly curved wall portion 13, which continues into a downwardly directed exit for the delivery of the coin into an opposed passage, chute or receptacle 14. It is the purpose of my invention

tion that true or designated coins shall take the course described. In their passage along the guide however, said coins will alight upon an arm 15 of a plate or body 16 which is pivoted at 17 to a lug 18 extended rearwardly from frame 1, said body having another, shorter arm 19 and constituting a magnet of which the arms 15, 19 are the respective poles. The pivot 17 is so located, at the lower part of body 16; that the arms tend to swing upwardly, but are held horizontal by reason of arm 15 engaging the lower edge of frame 1, said arm 15 being extended forwardly in advance of the front surface of the frame. The arm 19, which is shorter is entered into a slot 20 through the frame, its end being normally flush with the forward surface of the coin guide, which is slotted at 2^a to receive it, but capable of projecting beyond said surface if the device be rocked upon its pivot.

When a true or designated coin passes in the manner already described along the guide, and alights upon arm 15, the weight of such coin depresses arm 15, rocking the device upon pivot 17, and the degree of that depression is sufficient to provide a clearance between arm 15 and wall portion 13 to permit the coin to pass; whereas if the arm were held rigid the coin would become wedged between it and wall portion 13. This is what occurs to a disk or light weight coin that fails to depress arm 15.

It will be noted that the upper part of shield 3 is provided with side lugs 21, adapted to engage in bearing slots 22 formed in brackets 23 that project forwardly from guide 2; also that shield 3 has a curved lower portion 23^a that lies over the laterally extended portion of the coin guide-way, said lower portion being weighted, as at 24, to normally hold passing coins and spurious coins against the guide. When, however, the guide is swung upon its fulcrum, as by the previously described act in introducing a coin through slot 5, the shield is spread apart from the guide by reason of rearwardly projecting lugs 25 on the shield, which engage the frame 1 as the top part of the shield swings backwardly.

In the tilting of guide 2 and the spreading apart action of shield 3 a lightweight disk or spurious coin that may have become lodged upon arm 15, thus being removed from its support, will fall forwardly from that lodged position into a receptacle beneath provided therefor. Washers or disks having a central orifice and of sufficient weight to depress arm 15 will cause arm 19 to project forwardly through slot 20, thereby impaling such washer or apertured disk, holding it suspended until the guide is again tilted by the introduction of another coin.

The arms, 15 and 19, being the poles of

a magnet will attract and hold a magnetizable disk that reaches the arm 15, preventing it from following further along the path of a true coin, and such magnetizable disk will be ejected by tilting action of the guide.

It must be appreciated that coincident with the tilting and ejection action of guide 2, shield 3 is spread apart therefrom to facilitate the get-away of the ejected spurious coin, disk or washer.

Limiting means to the extent of the guide tilting and shield spacing movements are provided in the form of a lug 26 extended from the guide wall 12, in parallelism with the guide surface, said lug serving as a stop to engage the shield, which in turn prevents further forward movement of the shield.

In Fig. 2 I have shown a true coin 27 as falling through the chute 14, and a spurious coin 28 as ejected to be guided by wall 29 into a receptacle therefor.

Also I have shown a spurious coin 30 lodged upon arm 15.

As a washer the spurious coin appears impaled upon the projected arm 19, and if a magnetizable disk, then it is held by the poles 15 and 19 of the magnet.

Variations within the spirit and scope of my invention are equally comprehended by the foregoing disclosure.

I claim.

1. The combination with a coin box having a receiving slot, of a tiltable inclined guide displaceable by an entering coin, a shield hung upon said guide, said shield and guide forming a passage-way which directs true coins to a predetermined exit, lodgement means in said passage-way for spurious coins, and means for separating the shield from the guide in the tilting action of the latter to permit ejection of a lodged spurious coin.

2. The combination with a coin box having a receiving slot, of a tiltable inclined guide displaceable by an entering coin, a shield hung upon said guide, said shield and guide forming a passage-way which directs true coins to a predetermined exit, lodgement means in said passage-way for spurious coins, and means for separating the shield from the guide in the tilting action of the latter to permit ejection of a lodged spurious coin, said shield being weighted for its gravity return.

3. The combination with a coin box having a receiving slot, of an inclined frame, a guide tiltably mounted on said frame to be displaceable by an entering coin, a shield hung upon said guide, said shield and guide forming a passage-way which directs true coins to a predetermined exit, lodgement means in said passage-way for spurious coins, and means upon the shield that co-act

with the frame in the guide tilting action to separate the shield from the guide to permit ejection of a lodged spurious coin.

4. The combination with a coin box having a receiving slot, of an inclined frame, a guide tiltably mounted on said frame to be displaceable by an entering coin, a shield hung upon said guide, said shield and guide forming a passage-way which directs true coins to a predetermined exit, lodgement means in said passage-way for spurious coins, means upon the shield that co-act with the frame in the guide tilting action to separate the shield from the guide to permit ejection of a lodged spurious coin, and means for limiting the shield separating movement.
5. The combination with a coin box having a receiving slot, of an inclined frame provided with an aperture therethrough, a guide mounted on said frame, a lodgement device pivoted to said frame, said device having a longer arm which extends forwardly of the frame and a shorter arm whose end lies within the frame aperture, said device rocking under the weight of a true coin imposed upon its longer arm to permit the continued travel of a true coin, and means upon the guide co-acting with said longer arm to check the travel of a light weight coin or disk whose weight, im-
- posed on the longer arm, is insufficient to rock said device.
6. The combination with a coin box having a receiving slot, of a frame, a coin guide mounted on said frame, a magnet pivoted to said frame, one pole arm of said magnet extending normally in the path of passing coins, and being depressable by a true coin to permit passage thereof, and the other pole arm extending normally to the plane of the frame surface, whereby said magnet is enabled to engage a magnetizable disk entering into contact with said pole arms.
7. The combination with a coin box having a receiving slot, of a frame, a coin guide mounted on said frame, a magnet pivoted to said frame to engage magnetizable disks, the lower pole arm of said magnet extending normally in the path of passing coins and being depressable to permit passage thereof, and the upper pole arm extending normally to the plane of the frame surface, whereby a washer or the like having a central hole will become engaged by the upper pole arm as the magnet is rocked by the washer or the like falling upon and depressing the lower pole arm.

Executed this 24th day of January, 1925.

CHARLES J. PAULSON.
